UNITED STATES PATENT OFFICE.

BENJAMIN WOLF, OF PHILADELPHIA, PENNSYLVANIA, ASSIGNOR TO THE
NATIONAL METAL EDGE BOX COMPANY, OF NEW JERSEY.

DESIGN FOR A MATCH SAFE OR TRAY.

SPECIFICATION forming part of Design No. 30,228, dated February 21, 1899.

Application filed January 28, 1899. Serial No. 703,742. Term of patent 7 years.

To all whom it may concern:

Be it known that I, BENJAMIN WOLF, a citizen of the United States, residing at Philadelphia, county of Philadelphia, and State of Pennsylvania, have invented and produced a new and original Design for Match Safes or Trays, of which the following is a full, clear, and exact description, reference being had to the accompanying drawings, which form a part of this specification.

My design can best be described by referring to the accompanying drawings, in which—

Figure 1 is a perspective view of the match safe or tray from one end thereof, and Fig. 2 a perspective view of the same from the opposite end.

A A' are the two ends of the match safe or tray, and B B' the two sides. As may be seen, the two sides approach the two ends in a curve.

C is a separate piece of metal which rests within and at one end of the safe or tray and extends a short distance along the sides of the tray, being curved to conform to the junc-

ture of the end and sides of the safe. At the 25 sides projecting oblong tongues c' c' project from the piece C into indents in the sides of the safe or tray, forming on the exterior of the sides a raised projection c². Projecting from the end A' of the tray is the knob or projection 30 d, presenting a projecting knob or rounded appearance on the exterior of the end.

D is an overhanging flange which projects from the upper portion of the piece C. This overhanging flange D has its upper surface 35 serrated or notched.

Having now fully described my invention, what I claim, and desire to protect by Letters Patent, is—

The design for a match safe or tray substantially as shown and described.

In testimony of which invention I have hereunto set my hand, at Philadelphia, on this 26th day of January, 1899.

BENJAMIN WOLF.
